(57) **CLAIM**

The ornamental design for a detachable dental lingual bar as shown and described.

DESCRIPTION

FIG. 1 is a perspective view of a detachable dental lingual bar in an environment where detached and separated from a complementary detachable dental lingual bar, showing our new design;

FIG. 2 is a first perspective view of the detachable dental lingual bar of FIG. 1 in an environment where attached to the complementary detachable dental lingual bar;

FIG. 3 is a second perspective view thereof;

FIG. 4 is a top plan view thereof; and

FIG. 5 is a front elevation view thereof.

FIG. 6 is a first perspective view of a detachable dental lingual bar, showing our new design;

FIG. 7 is a second perspective view thereof;

FIG. 8 is a top plan view thereof;

FIG. 9 is a bottom plan view thereof;

FIG. 10 is a right elevation view thereof;

FIG. 11 is a left elevation view thereof;

FIG. 12 is a front elevation view thereof; and,

FIG. 13 is a rear elevation view thereof.

All broken lines are included for the purpose of illustrating use and environment and form no part of the claimed design.

1 Claim, 7 Drawing Sheets
